114,843

DESIGN FOR AN AIR SUPPLY DEVICE FOR
TREATING THE SCALP OR THE LIKE

Maximilian Ehrlich, Cedarhurst, N. Y., assignor to
J. P. Fischer, Inc., New York, N. Y., a corpo-
ration of New York

Application April 27, 1938, Serial No. 76,769

Term of patent 7 years

To all whom it may concern:

Be it known that I, Maximilian Ehrlich, a citizen of the United States, residing at Cedarhurst, L. I., in the county of Nassau and State of New York, have invented a new, original, and ornamental Design for an Air Supply Device for Treating the Scalp or the like, of which the following is a specification, reference being had to the accompanying drawing, forming part thereof.

The figure shown in the drawing is a perspec-

tive view of an air supply device for treating the scalp or the like showing my new design. A rear view of the device is like that shown except that the toggle switches and the switch plate are omitted.

I claim:

The ornamental design for an air supply device for treating the scalp or the like, substantially as shown and described.

MAXIMILIAN EHRLICH.
